EQUALIZED CELL-TYPE SHIELDED ENCLOSURE

Denney Williams, Silver Spring, Md.

Application April 18, 1955, Serial No. 502,130

17 Claims. (Cl. 174—35)

The present invention relates to interference reduction, and is more particularly concerned with a novel shielded enclosure for confining radio interference to a limited area or for maintaining a limited area substantially free of external radio interference. In this respect, the present invention is primarily concerned with a novel enclosure structure comprising a plurality of cell-type panels of screen construction, interconnected with one another in the manner to be described.

In the past, shielded enclosures have taken one of three standard forms. These have been termed, respectively, single-shielded structures wherein a substantially planar surface is utilized for interference reduction; double-shielded structures wherein a pair of screen surfaces spaced from one another are utilized for interference reduction; and cell-type structures wherein double-shielded structures are conductively coupled to one another thereby to form a continuous screen surface having at least two enlarged planar surfaces spaced from one another. The present invention is concerned with a modified form of such cell-type structure; and in particular, relates to such cell-type structure; incorporating, in addition, a further ungrounded or floating screen interposed between the aforescored two planar surfaces thereby to provide increased attenuation of radio interference and improved shielding characteristic for a composite shielded enclosure. In addition, the present invention relates to improved panel constructions of the equalized cell-type structure described, including the provision of novel screening material in conjunction with improved fastening and interlocking means for providing the enhanced operating characteristics effected.

It is accordingly an object of the present invention to provide an improved shielded enclosure.

A further object of the present invention resides in the provision of improved shielding means.

Still another object of the present invention resides in the provision of a novel panel construction for use with shielded enclosures whereby greater attenuation of radio frequencies is possible than has been the case heretofore.

A still further object of the present invention resides in the provision of an improved portable and prefabricated shielding enclosure.

Still another object of the present invention resides in the provision of a shielded enclosure which eliminates the necessity of solder connections or high resistance joints.

A further object of the present invention resides in the provision of a novel disposition of screen surfaces whereby more effective and efficient shielding may be obtained than has been the case heretofore.

In providing for the foregoing objects and advantages of the present invention, a shielded enclosure is effected comprising a plurality of interchangeable and interconnected shielding panels. These panels in turn comprise side panels interconnected with one another and including provisions for an access panel or door; and further include a plurality of top and bottom panels, once more

2

interconnected with one another and with the said side panels whereby a portable, prefabricated enclosure is effected.

As will be described subsequently, the several panels forming the sides, top and bottom of my novel shielded enclosure, are of cell-type construction and further include an equalizing screen disposed within the cell whereby improved attenuation is realized. The several panels are preferably constructed of selected, straight-grained, knot-free, Northern white pine, air and kiln-dried, with a moisture content not in excess of 10%, upon application of wood preservative. Each side panel is of the same physical size (preferably 40" in width and 8' in height), and universal mounting holes are provided therein whereby the said side panels may be readily disassembled from one another and interchanged with one another upon assembly. The said side panels, as will appear subsequently, are of double-frame construction and utilize mortise-and-tenon corner and cross-member joints thereby to give an extremely strong construction and to provide a desired separation between inner and outer screen surfaces mounted thereon, whereby the attenuation characteristics of the panel are increased. All peripheral edges of the several panels are of ship-lap construction, and preferably allow a minimum of 3" of contact surface at all joints whereby an overlap of an inner and outer screen at the said edges may be provided.

In addition to the foregoing, all panels have an equalizing screen placed in the double frame equidistant from the inner and outer screen; and the purpose of this equalizer is to provide an equal potential plane between the said inner and outer screen which will disperse any concentration spot voltage or standing waves throughout its surface, thereby to prevent such concentration from reaching the other screen in concentrated form. The inner and outer screens preferably comprise a composite screening material including a high permeability iron core having copper and silver plating thereon, whereby low contact silver-to-silver, or silver-to-silver oxide joints are effected between the said inner and outer screens, and the said screens are secured to the wooden frames discussed previously by silver plated staples whereby soldering and the possible high resistance joints attendant thereto may be eliminated. The center or equalizing screen has a fairly high characteristic impedance thereby to add to the total impedance losses between the inner and outer screens described; and the said center screen preferably comprises a high permeability iron core, plated with zinc (galvanized screen), thereby to increase the resistance of the said center screen and to allow a greater dissipation of any energy induced therein.

The ceiling and floor panels are of substantially the same mechanical and electrical construction as the side panels except that they are of increased length and the said ceiling and floor panels are once more interchangeable as was the case in respect to the several side panels. By providing such a shielded enclosure comprising equalized cell-type panels and by utilizing the special screen materials and non-solder joints of the present invention, an enclosed cubicle having extremely good attenuation characteristics is effected.

The foregoing objects, advantages, construction and operation of the present invention will become more readily apparent from the following description and accompanying drawings, in which:

Figure 1 is a perspective view of a shielded enclosure constructed in accordance with the present invention.

Figure 2 is a representation of an individual panel for use in the shielded enclosure of Figure 1 and constructed in accordance with the present invention.

Figure 3 is a view taken on section 3—3 of Figure 2.

Figure 4 is a view taken on section 4—4 of Figure 2.

Figure 5 is a view taken on section 5—5 of Figure 1.

Figure 6 is a representative of views taken on section 6—6 of Figure 1; and

Figure 7 is a greatly enlarged representation of an improved wire strand for use in the inner and outer screens of the shielded panels in accordance with the present invention.

Referring now to Figure 1, it will be seen that a shielded enclosure in accordance with the present invention may comprise a plurality of side panels 10 interconnected with one another and with a plurality of top panels 11 and a plurality of floor panels (not shown) of the same construction as the said top panels 11, whereby a shielded enclosure is provided. Each of the panels 10 and 11 comprises a frame construction of wood, as described above, and includes bracing strips 12, thereby to form a rigid mechanical configuration; and the several panels 10 and 11 (as well as the floor panels) are of cell-type screen mesh construction and include an equalizing center screen disposed between the inner and outer screens thereof, in the manner to be described. In addition, an access panel or door 13 is provided and the said door 13 is preferably constructed of water-proof marine plywood to decrease the possibility of door sagging. The access panel or door 13 closely resembles the several side panels 10, inasmuch as a certain amount of the plywood is cut out from the center thereof to reduce the door weight; and the door or access panel 13 is preferably bound by ferrous channels which are copper and silver plate. In addition, the jambs of the door 13 are preferably of the same material as the door itself, and are jig-bored whereby universal fasteners of the type to be described in respect to the several side panels, may be employed; and four ball bearing hinges (not shown) are mounted on the door jamb.

It has been found that the use of "dogs" for securing doors such as 13 is unnecessary insofar as resultant attenuation is concerned, and the present invention, therefore, preferably employs adjustable tension, hospital roller latches (not shown) disposed adjacent the top and bottom of the access panel 13 whereby access to the shielded enclosure is improved.

The floor-shielding panels of the cubicle are protected by an overlay of plywood flooring panels of proper dimensions to completely cover the floor cells, and all of the side, floor and overhead panels preferably employ the equalized cell-type structure discussed previously. In addition, one panel of the assembled enclosure includes provision (such as a power entrance cabinet) for the entrance of power lines and filters and the same panel, or another panel, may further include provision (such as a radio frequency access cabinet) for entrance of radio frequency transmission lines. In practice, the power entrance cabinet may include four filtered power line entrances, as follows: one 28 volt D. C.; two 115 volt 60 cycle lines; and one 115 volt 400 cycle line; and, as mentioned, each of these lines is preferably provided with filters which are fully shielded between the input and output of each filter. In this respect, the power line entrances and filters should provide an insertion loss of 100 db at all frequencies between 100 kilocycles and 1000 megacycles.

The radio frequency access cabinet may be of similar construction, and both the radio frequency cabinets and power entrance cabinets may comprise known constructions utilizing two "bells" (similar to transformer end bells), which bells are connected electrically adjacent their outside peripheries by the panel screening material utilized. Such power and radio frequency cabinets are well known to those skilled in the art and the particular construction of any such cabinet does not, per se, com-

prise the present invention inasmuch as many variations are possible.

An individual panel constructed in accordance with the present invention, and comprising one unit of the shielded structure shown in Figure 1, may be seen from an examination of Figures 2, 3 and 4. Such a panel may comprise an outer wooden frame 20 having a further inner frame 21 secured thereto by silver plated screws 23. The peripheral edges of the resulting panel are of ship-lap construction, and the outer panel 21 is covered by a screen mesh 24 extending around the frame and between the overlap junction between the panels 21 and 22. Similarly, the inner panel 22 is covered by a further screen mesh 25, once more extending around the said frame 22 and into the overlap between the panels 21 and 22. The screen materials 24 and 25 are secured to their respective frames by silver plated staples and the said outer and inner screens 24 and 25 contact one another in the junction between frames 21 and 22, thereby to provide a continuous electrical cell-type screen completely surrounding the composite frame 21—22.

In addition, a center or equalizing screen 26, serving the purposes discussed previously, is interposed between the frames 21 and 22, and may be attached by silver staples to either of the said frames. The said screen 26 is spaced from each of the screen surfaces 24 and 25, and is separated from the said screen surfaces 24 and 25 in the junction between frames 21 and 22, whereby the said center screen 26 floats free electrically from both of screens 24 and 25.

As has been mentioned previously, the inner and outer screens 24 and 25, utilized to form the cell-type screen structure of the present invention, preferably comprise a special screening material of the type shown, for instance, in Figure 7. Thus, the screen mesh comprising screen surfaces 24 and 25, employ strands of wire having an iron core 30 and the said core 30 is coated with a copper plating 31 which is in turn coated with a silver plating 32. Due to the provision of the external silver coating, and inasmuch as silver and silver oxide have the same electrical characteristics, the junction between frames 21 and 22, providing electrical continuity between the outer and inner screen surfaces 24 and 25, is of low resistance. Such structure provides a substantial improvement over prior constructions wherein soldered joints have been utilized, inasmuch as such soldered joints have been found to exhibit relatively poor surface contact and, in addition, have a tendency to corrode with age whereby high resistance contacts result.

The special mesh described and shown in Figure 7 further enhances the shielding characteristics of the composite enclosure for a number of reasons. Thus, the use of the high permeability iron core material 30 provides a low reluctance path to electromagnetic waves; and inasmuch as the several iron cores forming the screen mesh are insulated by a non-ferrous metal (copper), magnetic short-circuits within the mesh of the screen are eliminated, thus achieving less core loss. In addition, the use of copper and silver coatings on the core provide low effective resistance to electrostatic currents whereby low radiation resistance is effected. Again, as has been mentioned previously, the use of a silver coating as the outer material of the mesh results in the screen retaining its electrical characteristics even if the mesh thereof should oxidize on its surface. As a result of the foregoing construction, it has been found that the iron core gives extremely good attenuation at all frequencies below 500 kilocycles, with particular reference to the electromagnetic or H. field. The copper coating, in addition, gives further attenuation for intermediate frequencies up to very high frequencies and the silver coating in turn gives excellent attenuation in the V. H. F.—U. H. F. and microwave ranges.

During actual operation, within 100 feet of the enclosure, excellent attenuation has been achieved in the range

of .3 to 10 kilocycles and from 15 megacycles to 1000 megacycles. In this respect, it should be noted that the actual total attenuation provided by the screen structure described, particularly when employing the center or equalizing screen of the present invention, has thus far been outside the capacity of available test equipment; but certain obtained results are as follows:

Type of Test	Frequency of Test	Maximum Capability of Combined Test Equipment Used, db	Minimum Attenuation of Silver Grid Shielded Enclosure, db	Maximum Attenuation of Silver Grid (Beyond capacity of test equipment)
Electro magnetic (H field).	200 Kilocycles...	80	80	Undetermined.
Electrostatic (E field).	do	120	120	Do.
Do	1 Megacycle	120	120	Do.
Do	18 Megacycles	120	120	Do.
Do	400 Megacycles	120	120	Do.

As mentioned previously, the center screen 26, utilized in each of the panels of my novel shielded enclosure, is disposed substantially equidistant from the inner and outer screens 25 and 24, and provides an equal potential plane between the said inner and outer screens which disperses any concentrated spot voltage or standing waves throughout its surface. The said equalizing screen 26 exhibits a fairly high characteristic impedance and is preferably of galvanized construction. The screen type construction utilized in element 26 minimizes hysteresis and eddy current losses, which would reduce the efficiency of the shielding and which might occur with the use of solid metal constructions.

As has been discussed, the several panels comprising the sides of my shielded enclosure, and the several panels forming the top and bottom of my shielded enclosure, are respectively interchangeable and provide for ready disassembly whereby a relatively light, portable, and prefabricated enclosure is effected. The side panels as well as the individual top and bottom panels are interconnected with one another in the manner shown in Figure 5. Such interconnection may be effected by interposing a U-shaped channel 27 (preferably copper and silver plated) between adjacent panels, as shown, and by running bolts 28 and 29 through the said channel 27 and the sections 21 and 22 of the frame at right angles to one another. In this respect, the frames 21 and 22 are preferably provided with bolt holes 35 (see Figure 2), and the bolts 28 and 29 are preferably captive type hex-head bolts, whereby the possibility of lost bolts during assembling or dismantling operations, is eliminated. Once more (as was the case with respect to the iron mesh wire, the channel 27, the screen securing staples, and the screws 23), the bolts 28 and 29 are preferably silver plated to reduce losses and avoid high resistance contacts.

It will further be noted from an examination of Figure 5, that by bolting adjoining panels in orthogonal directions the channel 27 provides pressure between adjacent frame members 21, in two right angle directions, thereby to reduce contact resistance therebetween; and while Figure 5 has, for purposes of clarity, shown the said adjacent frame members 21 as slightly separated from one another, in practice the said adjacent frame will, due to proper choice of channel 27, be in close and forcible contact with one another.

The method of forming a corner joint, such as would occur at the corner of adjacent side panels, or between the top and side or bottom and side panels, has been shown in Figure 6. Due to the ship-lap construction employed, such corner constructions are readily effected and adjacent corner panels may once more be tightly held in contact with one another by further captive type hex-head bolts 36 and 37, utilizing the same bolt holes as were provided for the colinear panel arrangement shown in Figure 5.

When assembled in the manner described above, the several panels provide a unitary shielded enclosure, and each of the said panels in turn comprises a cell-type construction having inner and outer screens in electrical contact with one another and a centrally disposed equalizing screen spaced from each of said inner and outer screens. By such construction, and due to the provision of silver

staples, special mesh materials, and silver plated bolt and screw members, the overall attenuation of my novel shielded construction is far in excess of that accomplished heretofore.

While a preferred embodiment of the present invention has been described, it must be stressed that many variations thereof will be suggested to those skilled in the art, particularly in respect to the manner of interconnecting the several individual panels, and in respect to the disposition of an equalizing screen or screens within a cell-type panel. The foregoing description is, therefore, meant to be illustrative only and is not limitative of my invention and all such variations as are in accord with the principles discussed are meant to fall within the scope of the appended claims.

Having thus described my invention, I claim:

1. A shield panel structure for a shielded enclosure comprising a frame of insulating material, first and second substantially parallel conductive screen mesh surfaces supported by and spaced from one another on said frame, said first and second surfaces being electrically interconnected with one another adjacent the periphery of said frame thereby to form a substantially unitary cell-type screen defining an enclosed volume between said first and second screen mesh surfaces and said frame, and a third conductive screen mesh surface interposed in the said enclosed volume between said first and second screen mesh surfaces, said third screen mesh surface being supported by said frame in substantially parallel relation to each of said first and second surfaces, said third surface being electrically insulated from each of said first and second surfaces.

2. The structure of claim 1 wherein said third screen mesh surface comprises a material having higher electrical resistance than said first and second surfaces.

3. The structure of claim 1 wherein said third screen mesh surface comprises galvanized iron.

4. The structure of claim 3 wherein said first and second surfaces comprise screen mesh material having strands of iron core material successively coated with layers of copper and silver.

5. A shielded enclosure comprising a plurality of interconnected panels, each of said panels being of screen mesh cell-type construction, and each of said panels including a further equalizing screen surface centrally disposed within the screen mesh cell and electrically insulated from the screen mesh surfaces comprising said cell, said cell-type and equalizing screen mesh surfaces being carried by and supported on a common frame of insulating material with said equalizing surface being supported on said frame in completely spaced relation to said cell-type screen mesh surface.

6. The enclosure of claim 5 wherein said further equalizing screen surface comprises a material having higher

electrical resistance than that of the screen mesh comprising said cell.

7. A shielding panel for a shielded enclosure comprising first and second substantially rectangular shield surfaces spaced from one another and electrically interconnected to one another at their peripheral edges thereby to effect an enclosed cell-type shield, and a third substantially rectangular shield surface interposed between said first and second surfaces and electrically insulated from each of said first and second surfaces.

8. The combination of claim 7 wherein each of said first and second shield surfaces comprises a screen mesh surface, each of said mesh surfaces including interwoven strands of iron core wire having a copper coating thereon, and having a further coating of silver covering said iron core and copper coating.

9. A shielded enclosure comprising a plurality of side panels, a plurality of top panels, and a plurality of bottom panels interconnected with one another to form an enclosed cubicle, each of said side, top, and bottom panels comprising conductive screen mesh material of cell-type construction, and each of said panels including a conductive equalizing shield surface disposed within each of said cells and electrically insulated from the screen mesh comprising said cells.

10. The enclosure of claim 9 wherein said equalizing shield surface comprises galvanized iron screen mesh.

11. The enclosure of claim 9 wherein said conductive screen mesh material is silver plated on its exterior surfaces.

12. The enclosure of claim 9 wherein each of said panels is of ship-lap construction comprising non-conductive inner and outer frames fastened to one another, said screen mesh material of cell-type construction comprising inner and outer screens respectively supported by said inner and outer frames and in electrical contact with one another in the junction between said inner and outer frames.

13. The enclosure of claim 12 wherein said equalizing shield surface comprises a further screen surface supported between said inner and outer frames at the junction thereof, said further screen surface being spaced in said frame junction from the contacting surfaces of said inner and outer screens.

14. The enclosure of claim 9 wherein said conductive screen mesh material comprises interwoven strands of iron core wire having successive coatings of copper and silver on the said strands of wire.

15. A shielded enclosure comprising a plurality of interconnected screen mesh panels, each of said panels being of cell-type construction and comprising screen mesh material having interwoven strands of iron core wire with successive coatings of copper and silver thereon, each of said cell-type panels includes a further shielding surface of galvanized iron screen mesh disposed within said cell and electrically insulated from the screen mesh material comprising said cell.

16. The structure of claim 15 wherein each of said screen mesh panels includes a frame of ship-lap construction, an elongated metal channel disposed between each pair of adjacent panel frames, and means fastening each 25 of said adjacent panel frames to said metal channel.

17. The structure of claim 16 in which said channels are of a ferrous material and have successive coatings of copper and silver thereon.
